UNITED STATES PATENT OFFICE.

WILLIAM H. SCHOONMAKER, OF MONTCLAIR, NEW JERSEY.

VALVE-GEAR FOR GAS-ENGINES.

1,108,249.

Specification of Letters Patent.

Patented Aug. 25, 1914.

Application filed January 14, 1905. Serial No. 241,026.

To all whom it may concern:

Be it known that I, WILLIAM H. SCHOONMAKER, a citizen of the United States, and a resident of Montclair, in the county of Essex and State of New Jersey, have invented a new and Improved Valve-Gear for Gas-Engines, of which the following is a full, clear, and exact description.

The invention relates particularly to a two cycle gas or explosive engine, but it embodies various principles which are applicable to other types of engines which will fully appear hereinafter.

The object of my invention is to construct an engine which may be readily started and governed and kept under the complete control of the operator, both with respect to regulation of the speed and the reversal of its direction of movement.

To these ends the invention involves certain novel features of construction and arrangement of parts, which will appear hereinafter and be particularly pointed out in the claims.

Hereinafter reference will be had to the accompanying drawings which illustrate as an example the preferred embodiment of my invention, in which drawings like characters of reference indicate like parts in both of the views, and in which—

Figure 1 is a side elevation of a three cylinder engine embodying my invention, this view showing part of the cam shaft and its gear in section; and Fig. 2 is a vertical section through one of the cylinders on essentially the line 2—2 of Fig. 1.

The cylinders 10 may be water jacketed, if desired, and are mounted on a suitable base 11. Said cylinders are provided with valve boxes 12 having inlet ports 14 controlled by inwardly opening poppet valves 15. The cylinders are also provided with exhaust ports 16 uncovered by the pistons when their respective cranks are at the bottom centers or thereabouts.

17 indicates a source of supply of a combustible mixture of air and gaseous fuel under pressure sufficient to cause it to flow through the ports 14 and into the cylinders 10, the port arrangement being such that as the charge enters through the port 14 when the piston is at its outer position and the exhaust port uncovered, said charge will sweep through the cylinder, clearing out ahead of it the products of the previous combustion or explosion within the cylinder. In this

manner the charge enters the cylinder when the piston is at its outer position, and the cylinder is at the same time effectually scavenged of the burnt gases lying therein. 60

The pistons 18 are connected with the crank shaft 19 by rods 20 in the usual manner, and said shaft is provided with a spur gear 21 having at each side annular guide flanges 22. Said gear is meshed with a gear 23 of size equal to that of the gear 21 and splined on a sleeve 24, which in turn fits loosely on a full speed cam shaft 25.

26 indicates a lever or other suitable means for imparting a sliding movement to the sleeve 24. During this operation the gear 23 transmits rotary movement to the sleeve, and said gear is prevented from sliding by means of the guide flanges 22 on the gear 21. 70

27 indicates a bracket engaging the hub 75 of the wheel 23 and projecting from the frame of the engine, which serves also to hold the gear in place. The sleeve 24 is provided interiorly with a spiral groove 28 or equivalent screw device which receives a 80 pin or stud 29 carried on the cam shaft 25. Therefore, upon sliding the sleeve 24, since said sleeve is held from rotation by the gear 23 and its connections, the shaft 25 being incapable of axial movement (by reason of the 85 box 25^a or other means) will be forced to turn and in this manner the cams are shifted to reverse the engine, all of which will be brought out fully hereinafter.

Splined on the shaft 25 is a cam sleeve 30 90 which is formed with an annular bead 31 and a cam 32 for each inlet valve, said cams being spaced from their corresponding beads sufficiently to permit the stem rollers 33 to bear on the sleeve 30 between the cams 95 and the beads so that no movement will be imparted to the stem rollers. Said rollers 33 are attached to the valve stems 34 and these stems project through suitable stuffing boxes into connection with the respective 100 valves. As Fig. 2 illustrates, 35 indicates expansive springs acting between the valve boxes 12 and collars 36 on the stems 34. These springs serve to keep the valves 15 seated against the pressure of the gaseous 105 mixture in the conduit 17, and are overcome, however, by the action of the cams 32 and beads 31 so as to permit opening the valves.

37 indicates a governor which may be of any type desired. This governor is connected by a link 38 to a collar 39 carried on the shaft 25. Said collar is formed with

lugs 40 terminating in flanges 41. These lugs slide in openings 42 formed in the sleeve 30, and the end of the sleeve adjacent to said collar 39 is formed with flanges 43. 5 Between the flanges 41 and 43 a ring 44 bears, so that in this manner the collar 39 is connected with the sleeve to move the sleeve rightward by movement transmitted positively between the parts 41, 44 and 43, 10 and upon the leftward movement of the sleeve 39 said parts 41, 44 and 43 are inactive in transmitting movement to the sleeve. The sleeve, however, is moved leftward upon the leftward movement of the 15 collar 39 through the medium of an expansive spring 45 which encircles the shaft 25 and which is connected with the collar and with the sleeve. 20 indicates a lever or other means in connection with the sleeve 30 for shifting the same on the shaft 25. This lever is normally free to allow it to swing idly under the governor action imparted through the sleeve 30. A quadrant is shown in Fig. 1, 25 which may be employed to hold the lever if desired but in normal operation it is free. In the operation of the apparatus, assuming the gaseous mixture is under pressure in the conduit 17, to start the engine the lever 30 46 should be operated to slide the sleeve 30 toward the right so that the beads 31 ride under the stem rollers 33 and lift all of the inlet-valves from their seats. This will charge all of the cylinders with the gaseous 35 mixture, and since three cylinders are provided and their pistons are in connection with cranks at 120° angle on the shaft 19, it follows that at least one of these pistons will be at or near firing position. The lever 40 46 and sleeve 30 should now be returned to the position shown in Fig. 1, either by direct manual action or by releasing the manual pressure on the lever and allowing the pressure of the spring 45 to act. This closes 45 the valves 15 through the action of springs 35. An igniting apparatus, preferably of the electrical or other usual sort, as will be fully understood from the prior art, should be provided, and at this time the spark apparatus should be adjusted and operated so as to ignite the charge of the cylinder whose 50 piston is in position for firing. In Fig. 2 a jump spark igniter is conventionally illustrated at 50. An expansive stroke will then 55 follow and the engine will take up its movement in the usual manner. The governor 37 acting on the sleeve 30 through the spring 45, and collar 39 will move the sleeve leftward until the cams 32 act properly on the 60 valve-stems and then the operation of the engine becomes normal. It will be observed that the sleeve 30 will be continually under the action of the governor, and since the cams 32 taper from the plane of the sleeve 65 up to their highest point, by moving the

sleeve as described, the action of the inlet-valves may be regulated so as to regulate the charge admitted to the cylinders. In order to reverse the engine, the lever 26 should be operated, which will impart a 70 turning movement to the shaft 25 independently of that imparted to it from the gear 23, and this will give the sleeve 30 an independent turning movement, and in this manner the position of the cams 32 may be 75 so adjusted as to reverse the order of operation of the inlet valves and bring about a reversal of the movement of the engine. The sparking gear, of course, should be correspondingly reversed. The type of engine 80 here illustrated as having my invention applied thereto being of the two stroke cycle class and capable of operating in either direction, no change in the exhaust is necessary to effect this reversal. When the lever 85 46 is operated to slide the sleeve 30 rightward, the spring 45 is compressed, the sleeve then moving independently of the collar 39. Upon returning the lever 46 and sleeve 30, the parts again take the position shown in 90 Fig. 1, whereupon the action of the governor through the spring 45 will shift the sleeve 30 farther leftward and bring into operation the cams 32 as before described. 95 In connection with certain of the claims 100 in this case it is pointed out that the sleeve 30 and its cams constitute an actuating element for the valves; that is to say, it actuates them. And it is also pointed out that the valve driver is the crank shaft of 105 the engine or any intermediate element serving as the driving part for the valve mechanism in addition to any other purpose that it may serve. The gear 23 and shaft 25 therefore are moving or rotating members 110 respectively in connection with the valve actuating element and the valve driver or crank shaft, and the sleeve 24 is a relatively shiftable part which has sliding engagement with the gear and, by its spiral groove 115 28, screw connection with the shaft.

Various changes in the form, proportions and minor details of my invention may be resorted to at will, without departing from the spirit and scope thereof; hence I consider myself entitled to all such variations as may lie within the terms of my claims. 115

Having thus described the preferred form of my invention, what I claim as new and desire to secure by Letters Patent is: 120

1. In a gas engine, the combination with an inlet valve, of a cam shaft, fixed bearings for the shaft, means for rotating the shaft, means for turning the shaft independently of the rotating movement, a sleeve splined on the shaft and having a cam thereon for operating said valve, and means for manually shifting the sleeve longitudinally of the shaft. 125
2. In a gas engine the combination with a 130

valve thereof and its actuating cam and the prime mover shaft, of two rotatable members respectively in connection with said cam and shaft and a relatively shiftable part having screw connection with one of the rotatable members and longitudinal sliding connection with the other, whereby said shiftable part connects the two rotatable members to turn together, but by shifting said part the relative positions of the rotatable members are changed to change the action of the cam on the valve.

3. In a gas engine, the combination with the inlet valve thereof and its actuating cam and the prime mover shaft, of two rotatable members respectively in connection with said cam and shaft and a relatively shiftable part having screw connection with one of the rotatable members and longitudinal sliding connection with the other, whereby said shiftable part connects the two rotatable members to turn together, but by shifting said part the relative positions of the rotatable members are changed to change the action of the cam on the valve, means for supplying an explosive charge under pressure to the inlet valve and means for manually lifting the inlet valve from its seat.

4. In a gas engine, the combination with an inlet valve, means for supplying thereto an explosive mixture under pressure, of a cam shaft, fixed bearings for the shaft, means for rotating the shaft, means for turning the shaft independently of the rotating movement, a sleeve splined on the shaft and having a cam thereon for operating said valve, means for manually shifting the sleeve longitudinally of the shaft, and a bead on the sleeve adjacent to but separate from the cam to raise the valve from its seat upon manually shifting the sleeve.

5. In a gas engine, the combination with a valve thereof and its actuating cam and the prime mover shaft, of two rotatable members respectively in connection with said cam

and shaft and a relatively shiftable part having screw connection with one of the rotatable members and longitudinal sliding connection with the other, whereby said shiftable part connects the two rotatable members to turn together, but by shifting said part the relative positions of the rotatable members are changed to change the action of the cam on the valve, a governor and means placing it in connection with the cam, automatically to control the position of the cam without interference with the aforesaid action of said rotatable members.

6. The combination in a gas engine of means for supplying an explosive mixture under pressure, an inlet valve, a cam shaft and complementary devices for operating the inlet valve from the cam shaft, means for rotating the cam shaft from and in unison with the engine prime mover shaft, means for manually changing the position of the cam shaft relatively to the prime mover shaft, and means for lifting the inlet valve independently of the action of the cam.

7. The combination in a gas engine of the inlet valve thereof, a cam shaft and cam for operating the valve, a driving means, and devices for transmitting motion from said driving means to the cam shaft, such devices including parts having screw engagement with each other, and one of said parts being relatively movable to change at will the position of the cam shaft relatively to the driving means and without interfering with the normal rotation of the parts, means for supplying an explosive mixture under pressure to the inlet valve and means for manually raising the inlet valve.

In testimony whereof I have signed my name to this specification in the presence of two subscribing witnesses.
